UNITED STATES PATENT OFFICE.

HARWIN T. BARLET, OF LEBANON, PENNSYLVANIA.

NUT-LOCK.

SPECIFICATION forming part of Letters Patent No. 445,029, dated January 20, 1891.

Application filed April 10, 1890. Serial No. 347,302. (No model.)

To all whom it may concern:

Be it known that I, HARWIN T. BARLET, a citizen of the United States, residing at Lebanon, in the county of Lebanon and State of Pennsylvania, have invented a new and useful Improvement in Nut-Locks, of which the following is a specification.

My invention relates to an improvement in nut-locks which by means of an adjustable spring inserted and operating in the end of the screw - bolt and communicating with grooves in the nut locks the nut securely by expansion, or by contraction allows it to be turned either way on or off the screw, as occasion may require. This object is attained in the manner illustrated in the accompanying drawings, in which—

Figure 1 represents an elevation of a nut-lock embodying my invention. Fig. 2 represents a horizontal sectional view of the nut. Fig. 3 represents a vertical sectional view of the bolt and nut. Fig. 4 represents a cross-section of the bolt.

Similar numerals of reference indicate corresponding parts in the several figures.

Referring to the drawings, the numeral 2 designates the nut having interior recesses or grooves 4, said nut being fitted on the bolt 1, having an opening 5 in the end thereof. From 30 said opening 5 apertures 6 diverge to and extend through opposite sides of the bolt, said apertures being arranged obliquely and diverge from the same point, as shown by Fig. 3. A spring-key 3 is provided, the same having its shank occupying the opening 5, and provided with diverging legs 7, the head of said key being larger than the opening 5 in bolt 1, and forms means for readily manipulating the key. The inner walls of the apertures 6 form a V-shaped bed or peak 8, on 40 which the diverging legs 7 of the key are adapted to ride, so that when the key is forced in the legs are spread apart and so directed into the groove of the nut. When the key is withdrawn from locking action with the nut, the legs close, owing to their elasticity, and are brought within the apertures 6, so as to be free from contact with the nut, the latter thus being rotatable without liability of its 50 threads cutting said legs. The head 9 of the key projects from the end of the bolt, so that it is in convenient position for handling both in locked and unlocked positions. The outer end of the opening 5 is flared, to permit easy 55 insertion of the key in forcing the same to its

place in the bolt. The nut 2 is applied to the screw-threaded portion of the bolt, and the legs 7 of the key 3 are sufficiently compressed and inserted in opening 5 of the bolt. When said legs 7 are inserted in opening 5, as aforesaid, they extend into and through the oblique apertures 6, and the ends thereof engage the apertures or grooves 4 in the nut 2, thereby firmly locking the nut to the bolt. By withdrawing the key the legs 7 are contracted and 60 disengaged from the apertures or grooves 4 of the nut 2, and said nut may be freely turned in either one of two directions. It will be seen that the nut may be secured on the bolt at any point along the lines of contact of the 65 ends of the arms of the key with the said nut, thereby readily adapting the device to different thicknesses of material on which it may be employed.

Having thus described my invention, what 70 I claim as new, and desire to secure by Letters Patent, is—

1. A nut-lock consisting of an internally-grooved nut 2, a bolt having a longitudinally-extending opening 5 within the body thereof, 80 and diverging apertures 6, extending from the opening, with a peak 8 at the base of said opening and forming the lower walls of the apertures, a spring-key having a shank occupying said opening, and diverging legs occupying said apertures, said legs being adapted to be spread by said peak and when disengaged by the nut to be drawn into the body of the bolt, said parts being combined substantially as described. 85

2. In a nut-lock, a bolt having an opening 5 extending centrally therein and the apertures 6, the latter extending through the periphery of the bolt and in communication with the said opening, thereby forming a peak 8, 95 in combination with the spring-key 3, with diverging legs 7 and projecting head 9, said key, with its legs, being adapted to be drawn outward in said opening, substantially as described. 100

3. In a nut-lock, a bolt having an opening, and diverging apertures with a peak within the body thereof and a spring-key whose legs are adapted to ride on said peak so as to be spread and afterward close within said body, 105 substantially as described.

HARWIN T. BARLET.
